United States Patent Office.

CHARLES T. GILMOR, OF BALTIMORE, MARYLAND.

Letters Patent No. 96,421, dated November 2, 1869.

IMPROVEMENT IN TOBACCO-PRIZES.

The Schedule referred to in these Letters Patent and making part of the same

I, CHARLES T. GILMOR, of Baltimore, in the State of Maryland, have invented a new and useful Improved Horizontal Lever Tobacco-Prize.

Nature and Objects of the Invention.

My prize or press is intended primarily for farmers' use in packing raw tobacco into hogsheads, (hence its name,) and consists of a strong horizontal frame, adapted to receive and support the hogshead or other receiver, and a reservoir for the supply of the material thereto; a plunger or follower guided horizontally in said frame, and having a stem provided on each side of its transverse centre with one or more rows of vertical perforations, provided with shifting-pins; a long horizontal lever, fulcrumed on a fixed pivot in line with the transverse centre of the plunger, balanced in the frame, supported at its outer end by a ground-wheel, and adapted to have applied to it man or animal-power to reciprocate or vibrate it. The lever, in its vibrations, alternately acting on the pins in the series of perforations in the stem of the plunger on the respective sides of its fulcrum, and said pins being successively, as released, shifted back in their series of perforations, the necessary progressive movement of the plunger is obtained.

The means for applying the motion of the lever to the plunger and follower, and those for supporting the lever, constitute the improvements; being of novel character, simple, and strong, and adapting the prize especially for country build, by enabling its construction nearly entirely of wood.

Description of Drawings.

In the accompanying drawings—

Figure 1 represents a plan view, partly in section, of my improved tobacco-prize.

Figure 2, a vertical longitudinal section on the line *z z*, fig. 1.

Figure 3, a vertical transverse section on the line *y y*, fig. 1.

General Description.

In references to the drawings, similar marks indicate like parts in the several figures.

In the drawing—

A represents the frame.

B, the abutment in the same, for the support of the hogshead or reservoir.

C C C, transverse sills, forming the cradle for the reception of the hogshead and reservoir.

D D, uprights for the support of the contiguous ends of the hogshead and reservoir, being connected to the ground frame by hinge-joints, as shown in fig. 3, to adapt them to be folded down to allow the ready

introduction and removal of said hogshead and reservoir.

E, a double spring-catch for the support of the uprights D.

F G, transverse horizontally slotted timbers, for the guidance and support of the plunger; and

H, a longitudinal timber, on which the lever is balanced or its inner end supported.

I represents the hogshead or receiver; and

J, the "reservoir," which may consist of a hogshead with both ends removed, as shown.

K represents the plunger or follower.

L represents the lever, and *l* a horizontal elongated slot therein, for the reception or passage of the plunger K.

f represents a projection on the inner face of the timber F, in line with the centre of the plunger K, forming the fulcrum of the lever L.

M represents the ground wheel for supporting the outer end of the lever L.

N represents a hook, for the attachment of a team to the lever L, and O, fig. 1, a whiffletree attached thereto.

P P represent the pins inserted in the stem of the plunger K, for the engagement of the lever L, and *kk*, the perforations in the stem of the plunger K for the reception of said pins P.

Q Q represent metallic plates applied to the two faces of the lever L, where it rests on its fulcrum, and where it engages with the pins P, and on the opposing face of the timber F, to protect said surfaces, and prevent the rapid wear which would otherwise occur at these points.

R, fig. 3, represents the material being pressed.

To pack a hogshead, it, empty or loosely filled, with a filled reservoir, J, is placed in the cradle C of the frame, the former against the abutment B, and the uprights D turned into place, and secured by the catch F. The plunger K is then forced forward by hand as far as it can be easily, when the pins P, having been introduced in front of the lever L, a reciprocating or vibrating motion is imparted thereto by a team attached to the whiffletree O, or by other suitable means, and through said pins, which are alternately acted on, and shifted back during pressure on the other, a nearly continuous progressive motion of the plunger is produced. The plunger, as it is projected, forces the material from the reservoir J into the receiver I, and compresses it to the desired extent therein. Additional reservoirs may be introduced until the hogshead is filled to the desired extent, when it may be removed, an empty one introduced, and the operation repeated.

To remove the reservoirs and receivers, the pins P

are withdrawn, the plunger forced back until out of the reservoir, and the uprights D released from their catch F, and folded down, when they may be rolled out. For the adjustment of the pins, the operator or an assistant may be seated on the lever at its fulcrum.

The several rows of perforations, *k*, on each side of the fulcrum at different distances therefrom, adapt a fast, or slower and more powerful movement of the plunger to be obtained, as required at different stages of the operation.

By applying the power through a long lever, as proposed, an immense pressure may readily be obtained; while any loss of power which might otherwise result from supporting and overcoming the weight and friction of such a lever is effectually obviated by the mode of supporting the same described.

The entire prize may be easily and cheaply built, and is especially adapted for country use; the only metal work on it being the six wrought-iron plates Q, for the sides of the lever and the fulcrum timber, the two pins P, and a few bolts; all of which any blacksmith can make.

Although the device is primarily intended as a tobacco-prize for farmers' use, it may obviously be otherwise employed, and the material, and the form incident thereto, in either case be changed.

A suitable receiver adapted for the formation of bales may take the place of the hogshead and reservoir, and the adaptation of the frame for their reception be consequently omitted.

Suitable friction rollers may be employed to relieve the plunger from friction in its guides.

Suitable ratchet-racks on the stem of the plunger, and dogs or pawls hinged to the lever, may take the place of the perforations *k* and pins P; and by having said racks of sufficient width or duplicated, and adapting the pawls to be adjusted laterally, or duplicating them, the benefits of the multiplication of the rows of said perforations may be secured.

Claims.

I claim, as my invention—

1. The combination, with the horizontal plunger K, of the lever L, having a fixed fulcrum in line with the transverse centre of the stem of said plunger, the perforations *k* *k*, and pins P P, employed and operating substantially as described, for the purpose set forth.

2. The provision, in the stem of the plunger K, operated by the lever L, as described, of two or more longitudinal rows or series of the perforations *k* on each side of its transverse centre, at different distances therefrom, as described, for the purpose set forth.

3. In combination with the lever L, employed and operating substantially as described, the support F, and ground-wheel M, substantially as and for the purposes set forth.

To the above specification of my improved horizontal lever tobacco-prize, I have signed my hand, this 18th day of June, A. D. 1869.

C. T. GILMOR.
